(No Model.)

J. F. McLAUGHLIN.
TELEPHONIC TRANSMITTER.

No. 328,703.

Patented Oct. 20, 1885.

UNITED STATES PATENT OFFICE.

JAMES F. McLAUGHLIN, OF PHILADELPHIA, PENNSYLVANIA.

TELEPHONIC TRANSMITTER.

SPECIFICATION forming part of Letters Patent No. 328,703, dated October 20, 1885.

Application filed September 10, 1884. Serial No. 142,556. (No model.)

To all whom it may concern:

Be it known that I, JAMES F. McLAUGHLIN, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

10 Figure 1 is a vertical transverse section of a transmitter embodying my invention. Fig. 2 is a detail. Fig. 3 is a horizontal section of transmitter and a modified form or outline of my improvement, and Fig. 4 is an elevation 15 of the same.

My invention has relation to telephonic transmitters; and it has for its object to provide the transmitter with a tension device to prevent undue rattling of the diaphragm or to 20 avoid undue prolongations of the vibrations of the diaphragm when sound-waves are directed against it, whereby the efficiency of the instrument is increased or articulate speech transmitted with greater accuracy.

25 My invention accordingly consists of the combination, construction, and arrangement of parts, as hereinafter described and claimed, having reference particularly to a telephonic transmitter the diaphragm of which is provided with an outside bearing or pressure-arm having an adjusting-screw.

In the drawings, A represents the transmitter, having a diaphragm, B, carbon-block C, and inside pressure-adjusting arm, D, of the 35 usual or other suitable or desired construction.

E represents an arm or finger secured to the outside wall or surface of the transmitter-case a, and provided with an end stud or projection, e. This arm E is so located and arranged 40 that its stud e impinges against the outside central point of the diaphragm, as shown, so that said finger or its stud will subject the diaphragm to an outside central pressure, which

prevents rattling of the diaphragm or undue prolongation of its vibrations when sound-waves impinge against it, or make it vibrate in exact unison with such sound-waves, whereby the variations in the battery-current for the transmitter are made to correspond more accurately with such sound-waves and the efficiency of the instrument is increased. The arm E may be arranged vertically, as indicated in Fig. 1, or horizontally, as illustrated in Fig. 2, or otherwise, as desired. It may be straight or curved, as represented; or any suitable configuration may be given it. It may consist of a spring-arm, as shown in Figs. 1 and 2, or be rigid, and have an adjusting screw or nut, F, for varying the degree of the pressure of its stud e upon the diaphragm, as illustrated in Fig. 3.

I have shown my invention applied to that form of transmitter having a carbon or other block; but I do not confine myself thereto, as it may be used in connection with any other desired form of transmitter.

What I claim is—

1. In a telephonic transmitter, the combination, with its diaphragm, block C, and bar D, of an outside spring-arm, E, having stud e, 7c arranged to impinge against the center of the exterior surface of the diaphragm, substantially as shown and described.

2. In a telephonic transmitter, the combination of diaphragm B, block C, bar D, and spring-arm E, having set-screw F, and a stud, e, adapted to bear against the center of the outside or front surface of said diaphragm, substantially as shown and described.

In testimony whereof I affix my signature in 80 presence of two witnesses.

JAMES F. McLAUGHLIN.

Witnesses:

S. J. VAN STAVOREN,
CHAS. F. VAN HORN.
